UNITED STATES PATENT OFFICE.

WILLIAM R. FOX, OF GRAND RAPIDS, MICHIGAN.

TYPE-WRITING MACHINE.

1,247,950.

Specification of Letters Patent. Patented Nov. 27, 1917.

Application filed January 2, 1915. Serial No. 246.

To all whom it may concern:

Be it known that I, WILLIAM R. Fox, a citizen of the United States, residing at the city of Grand Rapids, county of Kent, and State of Michigan, have invented certain new and useful Improvements in Type-Writing Machines, of which the following is a specification.

This invention relates to improvements in type writing machines.

The objects of this invention are:

First, to provide an improved construction of universal bar for actuating the escapement mechanism and the ribbon vibrating mechanism, said universal bar being carried by the type bar segment and disposed so as to be actuated by the type bars as they approach printing position.

Second, to provide an improved ribbon vibrating mechanism which is actuated in advance of the escapement mechanism as the type bars approach printing position.

Third, to provide an improved ribbon vibrating mechanism for use with a bi-chrome ribbon and means for causing one color band of the ribbon or the other to be thrown to printing position or for shifting the parts to such a position that the ribbon vibrator will not be operated as for use in cutting stencils.

Fourth, to provide an improved stop means in connection with the ribbon vibrating mechanism to prevent overthrow of the ribbon vibrator.

Fifth, to provide an improved ribbon shift mechanism for changing from one color of ribbon to the other.

Further objects, and objects relating to structural details, will definitely appear from the detailed description to follow.

I accomplish the objects of my invention by the devices and means described in the following specification. The invention is clearly defined and pointed out in the claims.

A structure constituting a preferred embodiment of my invention is illustrated in the accompanying drawing forming a part of this specification, in which:

Figure I is a longitudinal, sectional eleva-

tion view through the central part of a typewriter showing a finger lever and connections from said finger lever to the type bar, the universal bar and the supporting means therefor, the ribbon vibrating mechanism, the escapement mechanism, and the ribbon shift mechanism, the type bar being shown by dotted lines raised to printing position. Only those parts of a typewriter are shown, which are essential to an understanding of my invention as I have not deemed it necessary to illustrate the other well known parts of a typewriter.

Fig. II is a fragmentary top plan view of a type bar segment showing the universal bar carried thereby and the connections from said universal bar to the escapement mechanism and the ribbon vibrating mechanism, the top plate of the machine and a portion of the ribbon vibrating mechanism being omitted for clearness.

Fig. III is a perspective view of the universal bar and the supporting means therefor, detached from its position on the type bar segment.

Fig. IV is a fragmentary detail sectional elevation view, similar to Fig. I, showing the ribbon vibrating mechanism set to bring the red portion of the ribbon to printing position.

Fig. V is a fragmentary sectional view similar to Figs. I and IV showing the ribbon vibrating mechanism set for stenciling so that the ribbon vibrating lever will not be actuated.

Fig. VI is an enlarged fragmentary, detail view corresponding to a part of Fig. I, showing the mechanism for actuating the ribbon vibrator, its engagement with the rear of the trip pin head and the stops to prevent overthrow of the ribbon.

Fig. VII is a fragmentary, enlarged view similar to Fig. VI showing in detail the shiftable selector 68 and its connection with the arm of the bell crank 53 of the ribbon vibrating mechanism.

Fig. VIII is a detail, sectional view on the line 8-8 of Fig. VII showing this connection in further detail.

Fig. IX is an enlarged, detail view in side elevation of the ribbon shift mechanism, showing the same set to bring the black portion of the ribbon to printing position.

5 Fig. X is a view similar to Fig. IX showing the ribbon shift mechanism set to bring the red portion of the ribbon to printing position.

10 Fig. XI is a view similar to Figs. IX and X showing the ribbon shift mechanism set for stenciling so that the ribbon will not be vibrated to lift the same to printing position.

15 Fig. XII is a fragmentary detail view in side elevation showing the lower end of the bell crank lever 87 provided with the triangular opening 91.

20 In the drawing similar reference characters refer to similar parts throughout the several views and the sectional views are taken looking in the direction of the little arrows at the ends of the section lines.

25 Considering the numbered parts of the drawing, I desire to state that my invention is adapted to and is here illustrated in connection with a Fox typewriter of the usual make. The details of the type bar action are not described at length in this specification as they form the subject matter of my Patent

30 No. 1,214,294, issued January 30, 1917.

The frame 1 carries a casting 2, the finger levers 3 having keys 5 being fulcrumed at their rear ends on the fulcrum wire 4 carried by said casting 2. Springs 6 connected 35 to said finger levers exert tension to pull them upwardly and to return the type bars to normal position. Rock levers 7 are fulcrumed on the fulcrum wire 8, carried by the casting 2, said rock levers being connected at 9 to the finger levers 3. A type bar segment 10 is shiftably supported in a manner well known in the art, said type bar segment being provided with an upper comb formed on the arc of a circle in which is 40 disposed a fulcrum wire 11 on which the type bars 12 are fulcrumed, the rear of said type bars being provided with cam slots 13. A fulcrum wire 15 is carried by the lower comb of the type bar segment and cam levers 45 14 are fulcrumed on said wire 15, the upper ends of said cam levers being connected by pivots 16 with the pitman links 17, the pivots 16 being disposed in the cam slots 13 of the type bars. The rear ends of the 50 pitman links 17 are connected to the upper ends of the rock levers 7 by pivots 18. This part of my structure is shown described and claimed in my patent above referred to.

55 A bracket 19 is secured to the rear of the type bar segment by the screws 20, said bracket having rearwardly projecting arms 21 between the ends of which the rock shaft 22 is journaled. The rock shaft is provided with a pair of downwardly projecting arms

23 to the lower ends of which ears 24, carried at the rear end of the universal bar frame 25, are pivotally secured. The curved universal bar 26 is carried by the forward end of the frame 25 in such a position adjacent the pivots of the type bars as to be 65 engaged by the shoulder 28 on the type bar 12 as it approaches printing position. This 70 forces the universal bar 26 and the frame 25 rearwardly, as shown by dotted lines in Fig. I. A finger 27 projects forwardly from the frame 25 through a suitable slot in the bracket 19 and assists in guiding and supporting the frame 25. A block 29 is carried by the rear of the frame 25 and a push pin 30 has its rear end 31 threaded into said 75 block 29 whereby the position of said push pin relative to said frame may be adjusted.

80 A bracket 32 is secured to the frame 1 provided with ears 33 in which the trip pin 34 is slidably mounted. Said trip pin has 85 at its forward end a broad head 35 which is engaged by the rear end of the pin 30. Escapement mechanism comprising the feed wheel 36 is secured to the top of the frame and the escapement pawl 37 is actuated by 90 the lever 38, the lower end of said lever being engaged by the rear end of the trip pin 34 to actuate the escapement mechanism. An adjustable stop pin 39 is carried by the bracket 32 and limits the movement 95 of lever 38, as shown in Fig. I.

A vibrator lever 40 is pivotally mounted at 41 in a bracket 42 carried by the top plate 43 secured to the frame. The top plate 43 has, at its forward side, downwardly extending ears 44. The ribbon vibrator guide 45 is provided at its lower end with ears 46 which are pivotally connected at 47 to the ears 44 on the top plate 43. A spring 48 connected to the ears 46 and to the top plate 100 105 tends to pull the ribbon vibrator guide toward the top plate. The upper end of the ribbon vibrator guide is disposed adjacent to the platen 49. The ribbon vibrator 50, through which the ribbon is guided, 110 is slidably mounted in the guide 45 and the lower end of the vibrator 50 is connected at 51 to the forward end of the lever 40. Lever 40 is provided with a notch 52 just in advance of the pivot 41 to accommodate 115 the rock shaft 22 on the universal bar when the type bar segment is raised to upper case position.

120 The bell crank 53 is pivotally mounted at 54 on the frame and is provided with a forwardly projecting arm having a forked end 55 which engages a pin 56 carried by the rear end of the vibrator lever 40, as clearly shown in Fig. I. The bell crank 53 has a rearwardly projecting arm 57, the 125 rear end of which is connected by spring 58 to an arm 59 pivotally mounted at 60 on the bracket 32. Arm 59 is provided with a slot

61 in which the set screw 62, carried by the bracket 32, is disposed. By this means, arm 59 can be adjusted to regulate the tension of the spring 58. Bell crank 53 has a downwardly extending arm 63 provided with a notch 64, a tail 65, and a pair of shoulders 66 and 67. A selector 68 is pivoted at 69 on the arm 70 and a plate 71 is secured to the upper end of said selector and spaced therefrom by the spacing block 72 and the shoulered rivet 73 which is carried by the plate 71 and the upper end of the selector 68. The lower end of the arm 63 of the bell crank 53 is disposed between said plate 71 and the upper end of the selector 68 as shown in Fig. VII, so that in one position of the selector 68, the rear of the rivet 73 engages the shoulder 66 on the arm 63. Selector 68 is shiftable to bring rivet 73 in line with notch 64 or shoulder 67. A tail 74 on selector 68 is adapted to engage a stop 75, struck up from the bracket 32, when the selector 68 is forced rearwardly upon the actuation of the universal bar. The arm 70 is secured to a pin 76 journaled in the bracket 32, and link 77 is also secured to said pin 76, so as to turn therewith. A forwardly extending link 78 is pivotally connected at its rear end to the link 77 by the pivot 79.

80 A bell crank lever 82 is carried by the frame 1 on the pivot 83 and carries a key 84 at its forward end. The downwardly depending arm 81 of the bell crank 82 is connected by the pivot 80 with the forward end of the link 78, so that said link 78 is reciprocated by the rocking of the bell crank lever 82. A spring 85 connects the lower end of the selector 68 below the pivot 69 with an ear 86 projecting from the arm 70, as shown in Figs. I, IV and V. The spring 85 together with the spring 58 acts to return the trip pin to normal position after it has been forced rearwardly. The bell crank 82 has a rearwardly projecting arm 98 which carries a pin 96. The bell crank 87 is pivoted to the frame at 88 and carries a key 89. The downwardly extending arm 90 of the bell crank 87 is provided with a triangular opening 91 therein, two sides of said opening being straight while the third side 92 is slightly concave, as shown clearly in Fig. XII. The arm 98 of the bell crank 82 extends in front of arm 90 of the bell crank 87, as shown in Figs. IX and XI inclusive. The pin 96 carried by the arm 98 is disposed in said triangular opening 91 as clearly shown in Figs. IX and XII inclusive. A lever 93 is pivoted to the frame at 94 and is disposed in front of the levers 82 and 87 and carries a key 95 at the forward end thereof. Lever 93 is provided with an oblong slot 97 in which the pin 96 carried by the arm 98 of the lever 82 is disposed.

The rear end of the rearwardly projecting arm 98 is provided with a laterally turned lug 99 to which one end of a U-shaped spring 100 is secured, the other end of said spring being secured to a pin 101 carried by the frame. A pin 102 is carried by the lower end of the arm 90 of the lever 87 and one end of a U-shaped spring 103 is secured to said pin 102, the other end of said spring being secured to a pin 104 carried by the frame. 65 70 75

From the description of the parts given above, the operation of this device should be very readily understood. The bracket 19 secured to the shiftable type bar segment carries the universal bar frame 25 which is 80 mounted between the ends of the arms 23 of the rock shaft 22, pivoted between the rearwardly projecting arms 21 of the bracket 19. This frame carries the curved universal bar 26 in such relation to the type bar 85 segment that the shoulders 28 on the type bars 12 strike said universal bar when the type bars are raised to printing position. As the shoulder 28 strikes the universal bar, 90 the same is forced backward as shown by 95 dotted lines in Fig. I. Push pin 30, which is carried by the frame 25, moves back as the universal bar is forced back and since the rear end of the pin 30 engages the broad trip pin head 35 which is carried by the trip pin 34 journaled in ears 33 on the bracket 32, said trip pin is forced back when the universal bar is actuated. The rear end of this trip pin engages the lever 38 to actuate the feed pawl 37 to operate 100 the escapement mechanism.

The rear face of the head 35 engages the rivet 73 on the upper end of the selector 68 to force the same backward. The ribbon is vibrated by means of the ribbon 105 vibrator lever 40, the front end of which is secured to the lower end of the ribbon vibrator while the rear end is engaged by the forked end 55 of the bell crank 53. The selector 68 may be shifted to anyone of 110 three positions by means of the link 78, the connecting link 77 and the arm 70. In one position, the rear face of the rivet 73 engages the shoulder 66 on the arm 63, so as to shift the black portion of the ribbon 115 to printing position. As the head 35 is forced back by the push pin 30, rivet 73 engaging the shoulder 66 forces the arm 63 backward and vibrates the lever 40 sufficiently to raise the black portion of the ribbon to printing position. Selector 68 may be shifted so that the rivet 73 engages the shoulder 67 on the arm 63. As this shoulder 67 is nearer the pivot point 54 of the bell crank, when the push pin forces 120 back the head 35, the bell crank is given a greater movement than it is in the lower position so that the vibrator lever 40 has a 125

larger movement and shifts the ribbon so as to bring the red portion thereof to printing position. The selector 68 may be shifted to an intermediate position in which 5 the rivet 73 is in line with the notch 64 in the arm 63. In this position, when the universal bar is actuated and the push pin 30 forced rearwardly, the rivet 73 is forced back by its engagement with the head 35 10 into the notch 64 and does not actuate the bell crank 63 or the vibrator lever 40. In this position, the ribbon is not shifted so as to be interposed between the type and the platen. This is the position of the parts 15 which is used in cutting stencils. A spring 58 secured to the arm 57 of the bell crank 53 is connected to the arm 59 and this arm 59 may be adjusted by means of the set screw 62 and the slot 61 so as to vary the 20 tension of the spring 58.

The ribbon shift mechanism is actuated by keys 84, 89 and 95 on the levers 82, 87 and 93 respectively. In Figs. I and IX, the parts are shown in such a position that 25 the black portion of the ribbon is shifted to printing position when the universal bar is actuated. In Figs. IV and X, the parts are shown in such relation that the red portion of the ribbon is shifted to printing 30 position. In Figs. V and XI, the parts are shown in position for stencil cutting, so that the ribbon vibrator is not actuated when the universal bar is actuated.

The lever 87 has the triangular opening 35 91, one side of which is concave as at 92. This concave side is drawn on the arc of a circle having its center on the pivot 83 as shown in Figs. IX and X. Fig. IX shows the parts in such position as to shift the 40 ribbon so that the black portion thereof will be brought to printing position. When it is desired to bring the red portion to printing position, the key 84, marked "red", is depressed. This throws the pin 96 carried by 45 the arm 98 of the lever 82 from the lower corner of the triangular opening as shown in Fig. IX to the upper corner thereof as shown in Fig. X. This pin rides on the concave side 92 and does not effect the bell 50 crank lever 87. The pin is held in the corner to which it is brought by the shifting of the lever by means of the springs 100 and 103. The depression of the key 84 serves to rock the bell crank lever 82 so as 55 to force forward the link 78 and said link 78 being connected to the short link 77, rocks the arm 70 to force upwardly the selector 68 so as to carry the rivet 73 to its upper position where it engages the shoulder 67 60 on the arm 63. When the parts are in either of the positions shown in Figs. IX and X, they may be brought to stencil cutting position by depressing the key 89 at the end of the lever 87 and thus rocking the latter upon its pivot 88. In either position the edge of 65

the triangular opening 91 engages the pin 96 and the pin is brought to the corner of the triangular opening shown in Fig. XI. When the parts are in the position shown in Fig. IX, when the bell crank lever 87 is 70 rocked, the pin 96 riding on the edge of the triangular opening 91, lifts the arm 98 of the bell crank 82 and moves forward the link 78 to bring the selector 68 and the rivet 73 to the intermediate position in which it 75 is in line with the notch 64. If the parts are in the position shown in Fig. X, the rocking of the lever 87 causes the edge of the triangular opening to engage the pin 96 and depresses the arm 98 of the bell crank 80 82 so as to move rearwardly the link 78 to bring the selector 68 from the upper to the intermediate position in which it is in line with the notch 64. The springs 100 and 103 hold the parts in the position to which 85 they are brought and hold the pin 96 in that corner of the triangular opening to which it has been brought by the actuation of the levers.

The universal bar is carried by the type 90 bar segment and actuates the trip pin head 34 through which the escapement mechanism and the ribbon vibrating mechanism are actuated. The pin 30 and the trip pin head 35 are disconnected so that the pin 30 95 can be shifted relative to the head 35 as the segment is shifted without changing the operative relations of these parts.

The spring 85 engaging the lower end of the selector 68 and tending to throw the upper end thereof forwardly and the spring 58 connected to the rearwardly extending arm 57 of the bell crank 53 and tending to throw the arm 63 forwardly, both serve to return the slidible trip pin 34 to its normal 100 position after it has been forced rearwardly upon the actuation of the universal bar. The stop 75 on the bracket 32 co-operates with one or the other of the stops 74 and 65. The stop 74 is carried by the upper 110 end of selector 68, and when said selector is in its lower position with the rivet 73 engaging the shoulder 66, the rearward movement thereof brings the stop 74 into engagement with the stop 75 to limit the rearward 115 movement of the selector 68 and consequently to limit the movement of the ribbon vibrator and to prevent overthrow of the ribbon. When the selector 68 is shifted to its upper position with the rivet 73 in 120 engagement with the shoulder 67, the rearward movement of the selector brings the tail 65 on the lower end of the arm 63 into engagement with the stop 75 and thus limits the movement of the vibrator to prevent 125 overthrow of the ribbon.

I am aware that the particular structure which I have here shown is susceptible of considerable variation without departing from the spirit of my invention and, there- 130

fore, I do not wish to be restricted to the same. I have found, however, that this form is to be preferred and, therefore, I desire to claim the same, specifically as well as broadly, as indicated by my appended claims.

Having thus described my invention, what I claim as new and desire to secure by Letters Patent is:

10 1. In a typewriting machine, the combination of a ribbon vibrator, a vibrator lever pivoted in the frame of the machine and connected to said vibrator; a bell crank lever pivoted in the frame of the machine and having a forwardly projecting arm engaging the rearwardly extending arm of said vibrator lever and a downwardly depending arm; a universal bar structure disposed to be actuated by the type bars as they approach printing position; and a selector actuated by said universal bar structure and adapted to engage the downwardly depending arm of the bell crank to actuate said ribbon vibrator; all coacting substantially 25 as described and for the purpose specified.

2. In a typewriting machine, the combination of a shiftable type bar segment; a universal bar structure carried by said segment and disposed to be actuated by each of the 30 type bars as it approaches printing position; a push pin carried by said universal bar structure; a bracket secured to the frame of the machine; a trip pin slidably mounted in said bracket and provided with a broad 35 head engageable by said push pin in all positions of the type bar segment; a ribbon vibrating lever; a selector extending behind said trip pin head and provided with a stop; a stop on said bracket; said ribbon 40 vibrating lever being provided with an arm extending behind said trip pin head and engageable by said selector, said arm being provided with a stop; and means for shifting said selector to bring the engaging portion 45 thereof in line with different portions of said arm; said stop on said bracket being so disposed as to be engaged by either the stop on the selector or the stop on said arm depending upon the position of said 50 selector; all coacting substantially as described and for the purpose specified.

3. In a typewriting machine, the combination with a plurality of type bars; of a universal bar structure disposed to be actuated by each of said type bars as it approaches printing position; a selector actuated by said universal bar structure; a ribbon vibrating lever having an arm engageable by said selector; means for shifting said selector so as to engage said arm at different distances from the fulcrum of said lever; a fixed stop; a stop on said selector adapted to engage said fixed stop when the selector is in one position; a stop on said arm adapted 65 to engage said fixed stop when said se-

lector is in another position, all coacting substantially as described and for the purpose specified.

4. In a typewriting machine, the combination with a plurality of type bars; of a universal bar structure disposed to be actuated by each of said type bars as it approaches printing position; a selector actuated by said universal bar structure; a ribbon vibrating lever having an arm engageable by said selector; means for shifting said selector so as to engage said arm at different distances from the fulcrum of said lever; a fixed stop; a stop on said selector adapted to engage said fixed stop when the selector is in one position, all coacting substantially as described and for the purpose specified.

5. In a typewriting machine, the combination with a plurality of type bars; of a universal bar structure disposed to be actuated by each of said type bars as it approaches printing position; a selector actuated by said universal bar structure; a ribbon vibrating lever having an arm engageable by said selector; means for shifting said selector so as to engage said arm at different distances from the fulcrum of said lever; a fixed stop; a stop on said arm adapted to engage said fixed stop when said selector is in one position; all coacting substantially as described and for the purpose specified.

6. In a typewriting machine, the combination of a shiftable type bar segment; a universal bar structure carried thereby and disposed to be actuated by each of the type 100 bars as it approaches printing position; a trip pin slidably mounted in the frame and having a broad head engageable by said universal bar structure in all positions of the type bar segment; and a selector engaging 105 the rear face of said trip pin head and shiftable relative thereto and adapted to actuate ribbon vibrating mechanism; all coacting substantially as described and for the purpose specified.

7. In a typewriting machine, the combination with a ribbon vibrating lever, of means for actuating said ribbon vibrating lever comprising a link, a bell crank pivoted to the frame and having a forwardly projecting arm carrying a key, a downwardly depending arm connected to the forward end of said link, and a rearwardly extending arm carrying a pin; a U-shaped spring having one end secured to the frame of the machine and the other connected to the rear end of said rearwardly extending arm; a second bell crank pivotally mounted on said frame and having a forwardly projecting arm provided with a key, and a downwardly extending arm having a triangular opening therein, one edge of said opening being slightly concave; the pin carried by said first named bell crank being disposed in said triangular opening in contact with the edge thereof; a 120 125 130

- pin carried by the lower end of said downwardly extending arm; a U-shaped spring fixed at one end to the frame and connected at the other end to said pin; and a lever 5 pivotally mounted on the frame, having a key at its forward end and provided with a slot in which said first named pin is disposed; all coacting substantially as described and for the purpose specified.
- 10 8. In a typewriting machine, the combination with a ribbon vibrating lever, of means for actuating said ribbon vibrating lever comprising a link, a bell crank pivoted to the frame and having a forwardly projecting arm carrying a key, a downwardly depending arm connected to the forward end of said link, and a rearwardly extending arm carrying a pin; a second bell crank pivotally mounted on said frame and having a forwardly projecting arm provided with a key and a downwardly extending arm having a triangular opening therein, one edge of said opening being slightly concave; the pin carried by said first bell 15 crank being disposed in said triangular opening in contact with the edge thereof; a lever pivotally mounted on the frame having a key at its forward end and provided with a slot in which said pin is disposed; and spring 20 means for holding said levers in the position to which they are brought by the depression of one of said keys, all coacting substantially as described and for the purpose specified.
- 25 9. In a typewriting machine, the combination with a ribbon vibrating lever, of means for actuating said ribbon vibrating lever comprising a link, a bell crank pivoted to the frame and having a forwardly projecting arm carrying a key, a downwardly depending arm connected to the forward end of said link, and a rearwardly extending arm carrying a pin; a second bell crank pivotally mounted on said frame and having 30 a forwardly projecting arm provided with a key and a downwardly extending arm having a triangular opening therein; the pin carried by said first bell crank being disposed in said triangular opening in contact with the edge thereof; a lever pivotally mounted on the frame having a key at its forward end and provided with a slot in which said pin is disposed; and spring 35 means for holding said levers in the position to which they are brought by the depression of one of said keys, all coacting substantially as described and for the purpose specified.
- 40 10. In a typewriting machine, the combination with a ribbon vibrating lever, of means for actuating said ribbon vibrating lever comprising a link, a bell crank pivoted to the frame and having a forwardly projecting arm carrying a key, a downwardly depending arm connected to the forward end of said link, and a rearwardly extending arm carrying a pin; a second bell crank pivotally mounted on said frame and having 45 a forwardly projecting arm provided with a key and a downwardly extending arm having a triangular opening therein; the pin carried by said first bell crank being disposed in said triangular opening in contact with the edge thereof; a lever pivotally mounted on the frame having a key at its forward end and provided with a slot in which said pin is disposed; and spring 50 means for holding said levers in the position to which they are brought by the depression of one of said keys, all coacting substantially as described and for the purpose specified.
- 55 11. In a typewriting machine, the combination with a ribbon vibrating lever, of means for actuating said ribbon vibrating lever comprising a link, three levers pivotally mounted on the frame; connections from said levers to said link whereby on the depression of anyone of said levers said selector is shifted to one of three predetermined positions; and means whereby on the depression of anyone of said levers, the lever last depressed is returned to normal position, all coacting substantially as described and for the purpose specified.
- 60 12. In a typewriting machine, the combination with a ribbon vibrating lever, of means for actuating said ribbon vibrating lever comprising a link, three levers pivotally mounted on the frame; connections from said levers to said link whereby on the depression of anyone of said levers said selector is shifted to one of three predetermined positions; all coacting substantially as described and for the purpose specified.
- 65 13. In a typewriting machine, the combination with a plurality of type bars; of a universal bar structure disposed to be actuated by said type bars as they approach printing position; a selector actuated by said universal bar structure; a ribbon vibrating lever having an arm engageable by said selector to actuate the lever; and means for shifting said selector to engage said arm at different distances from the fulcrum of said lever, comprising an arm pivotally mounted on the frame, said selector being pivotally mounted on said arm; a second arm secured to said first arm and extending at an angle thereto; a link connected to said second arm; means for reciprocating said link to shift said selector to anyone of a predetermined number of positions; and means for holding said link in the position to which it has been shifted, all coacting substantially as described and for the purpose specified.
- 70 14. In a typewriting machine, the combination with a plurality of type bars; of a universal bar structure disposed to be actuated by said type bars as they approach printing position; a selector actuated by said universal bar structure; a ribbon vi

brating lever having an arm engageable by said selector to actuate the lever; and means for shifting said selector to engage said arm at different distances from the fulcrum of
5 said lever, comprising an arm pivotally mounted on the frame, said selector being pivotally mounted on said arm; a second arm secured to said first arm and extending at an angle thereto; a link connected to said
10 second arm; means for reciprocating said link to shift said selector to anyone of a predetermined number of positions, all co-acting substantially as described and for the purpose specified.

In witness whereof, I have hereunto set 15
my hand and seal in the presence of two
witnesses.

WILLIAM R. FOX. [L. S.]

Witnesses:

LILLIAN THURSTON,
HENRIETTA L. TERMEER.
